SNAP FASTENER

Frederick H. Peterson, Watertown, and Rollin R. Clarke, Waterbury, Conn., assignors to The Patent Button Company, Waterbury, Conn., a corporation of Connecticut

Application May 8, 1944, Serial No. 534,604

4 Claims. (Cl. 24—216)

Our invention relates to new and useful improvements in snap fasteners and more particularly to the socket member of the snap fastener.

In the present application, the socket member is so made that a part of the same is provided with these concentrically arranged prick punches or perforations to guide the prongs into position, but as the plate is an integral part of the body or socket member, it eliminates an assembling operation.

Still another object of the invention is to provide a socket formed of but one piece rather than the two pieces and to provide, of course, the clamp plate which is to be driven through the cloth and the perforations in the plate and then deformed to tightly hold the socket member to its cloth.

Still another object of the invention is to provide a socket made of one piece wherein the same type of clamp plate may be utilized either with the present form of invention or with the invention disclosed in the companion application.

Still another object of the invention is to provide a socket that may be stamped and rolled from one piece of metal to thus cut down any assembling operations, and with which, of course, a clamp plate will be used to hold the socket member to its cloth.

Still another object of the invention is to provide a socket member which is so constructed that, regardless of the rotated position of the prongs of the clamp member in an attaching machine, the prick punches or small perforations will quickly adjust the prongs into a desired position so that the prongs will be readily guided and deformed within a receptive channel in the socket member to thus tightly clamp the socket member to its cloth.

With these and numerous other objects in view, the invention consists of new and novel constructions and combination of parts as will be herein-after more fully described.

Referring now to the drawing showing the preferred embodiment:

Fig. 1 is a top plan view of the socket member attached to its piece of cloth,

Fig. 2 is a bottom plan thereof.

Fig. 3 is an enlarged horizontal section taken on line 3—3 of Fig. 1, the stud being shown in dotted lines,

Fig. 4 is an enlarged top plan view of the body member,

Fig. 5 is a view similar to Fig. 3 but before the socket is clamped to its cloth, and

Fig. 6 is a sectional view of the clamp plate showing one of its prongs.

Referring now to the several views, there may be seen what we term a clamp plate 1, having its outer edges slightly dished, the plate being cut out centrally as at 3, and then slightly cut back as at 4 but leaving the metal to form two prongs 5, which are then bent downwardly at right angles to the body of the plate.

Referring for the moment to Fig. 3, we have shown the clamp plate with its prongs 5, as having passed through the cloth 6, to hold the socket member 7, in position. Also for the sake of clearness of illustration, we have shown in dotted lines the stud 8, which is to be received by the socket member 7.

Referring now to Figs. 3 and 5, there may be seen the inwardly extending rim 9, which is formed at the bottom of the substantially cylindrical wall 10, which wall is provided with a plurality of slots 11 that extend substantially throughout the height of the wall 10, to thus provide a plurality of resilient gripping fingers 12.

It is these fingers 12 that snap over and off of the head of the stud 8, when the snap fastener is attached or removed from its stud.

The metal of the wall 10, is bent back on itself as at 13, but is slightly spaced from the rear of the wall 10, as in the space is to be tucked the outer peripheral edge of the body member 7 when it is in its final form.

The metal that is bent back on itself is then provided with a slightly lowered depressed channel 14, and formed in the bottom of this concentrically arranged channel is a plurality of prick punches or relatively small perforations 15, as may be seen in Fig. 4. The outer wall of the concentric channel 14 then extends outwardly in a horizontal position to form the rim 16.

Extending downwardly from the rim 16 the metal is bent in a semicircular manner to form the receptive channel 17, and the metal which is the outer peripheral edge before the body or socket member 7 is formed, is then tucked between the concentric depressed channel 14 and the rear of the upstanding cylindrical wall 10, to thus provide an integral socket member of relatively great strength.

To secure the socket 7 in place, the clamping plates 1 will be placed in one hopper of an attaching machine (not shown) while the body member or socket 7 will be placed in a second hopper, and the two parts fed to an attaching station.

The cloth 6 or the fabric will then be placed between the clamping plate 1 and the socket member 7 and a plunger of the attaching ma-

chine descends to force the prongs 5 through the cloth 16.

Then, due to the multiplicity of prick punches in the depressed channel 14, the diametrically opposed prongs will locate certain prick punches 15 and be forced through the metal, and the prongs 5 then impinge on the bottom walls of the channel 17, where they will be guided and deformed as shown in Fig. 3, to tightly grip the cloth 6 between a clamping plate 1 and socket member and, in turn, fasten the socket member to the cloth.

Should it so happen that the diametrically opposite prongs are not in direct alignment with any certain prick punches or indentations, still the prick punches or indentations are so close together that the prongs will rotate slightly in either direction to thus find the adjacent ones.

Furthermore, the prongs 5 in forcing their way through the metal will be tightly gripped about midway the length of the prongs, while the outer ends of the prongs will also be jammed and deformed against the curved inner walls of their channel 17. This makes for an exceedingly sturdy fastener and after the clamp plate is once driven into place, there is very little likelihood that the socket will ever become loose with respect to its cloth.

Furthermore, by providing the prick punches or small openings 15, not only will the prongs be registered and gripped as heretofore mentioned, but in addition, there is little likelihood of the metal of the socket member 7 being jammed inwardly due to possibly relatively blunt prongs 5.

From the foregoing, it will be seen that we have provided an extremely efficient and simple snap fastener socket that is to be formed of one piece of metal, but with which, of course, there will be used a clamping plate to hold the socket to its cloth.

It will also be seen that we have produced a snap fastener wherein the prongs will readily find their true position to be driven through the socket member and there gripped and deformed to hold the socket member tightly to its cloth.

Many slight changes may be made without in any way departing from the spirit and scope of the invention.

Having thus described our invention what we claim as new and desire to secure by Letters Patent is:

1. In a socket member a one piece body member having slotted walls forming spring fingers and defining the socket chamber, an outwardly spaced channel formed in the body member and extending in a plane slightly below the top walls of the said socket chamber, a peripheral rim and a second deeper channel formed in the body member and extending under the first mentioned channel; together with a clamping plate provided with prongs, the first mentioned channel having a plurality of indentations in its bottom

wall, the prongs of the clamping plate adapted to register with said indentations and be deformed in the second mentioned channel during attaching operation to thus secure the socket 5 to its carrying medium.

2. In a one piece socket member for snap fasteners, a wall defining a centrally arranged socket and spring retaining fingers, a concentrically formed channel provided with a plurality of spaced openings, a semicircular wall forming a second channel and spaced beneath the first mentioned channel and the inner end of the second channel wall tucked behind the wall defining the socket; together with a clamp plate provided with prongs, said prongs adapted to register and pass through said minute openings in the first mentioned channel and be deformed and clinched in the second mentioned channel to thereby hold the socket member to its carrying medium.

3. In a socket member for a snap fastener, a one piece body member having an upstanding central wall, the lower edge of which extends inwardly, the said wall being slotted to form a plurality of spring fingers adapted to engage the head of a stud, a depressed channel arranged concentrically to the said wall and in a plane slightly below the upper edge of the upstanding central wall, said channel provided with a plurality of spaced indentations, a rim extending slightly beyond the depressed channel, a second concentric channel formed beneath the first mentioned channel and the outside edge of the metal forming the second channel being positioned behind the said central wall; together with a clamping plate having prongs adapted to register with the indentations in the walls of the first mentioned channel during attaching operation and be deformed within the second mentioned channel to thereby hold the socket member to its cloth.

4. In a socket member for a snap fastener, a body member having a central slotted cylindrical wall, the lower edge of which extends inwardly to form a plurality of spring fingers, the upper portion of the wall bent back on itself and then slightly upwardly to form a depressed concentric channel, the said channel provided with spaced prick punches, the outer wall of the channel provided at its upper edge with an outwardly extending rim and a semicircular wall extending from the rim under the depressed channel, and the edge of the wall positioned behind the cylindrical slotted wall; a clamping plate having prongs, the latter adapted to pass through the said registering prick punches in the plate during an attaching operation and be deformed by the said semicircular walls to tightly hold the body member of the clamping plate to its fabric.
